UNITED STATES PATENT OFFICE.

JAMES B. BAUM, OF GRAND JUNCTION, COLORADO, ASSIGNOR TO THOMAS P. McGUIRE, OF GRAND JUNCTION, COLORADO.

CLOTHES-RACK.

No. 895,329.

Specification of Letters Patent.

Patented Aug. 4, 1908.

Application filed August 2, 1907. Serial No. 386,777.

To all whom it may concern:

Be it known that I, JAMES B. BAUM, a citizen of the United States, residing at Grand Junction, in the county of Mesa and State of Colorado, have invented new and useful Improvements in Clothes-Racks, of which the following is a specification.

This invention is an improved clothes rack for application to the foot of a metallic bedstead, and which may be readily removed therefrom, as hereinafter described and claimed.

The object of this invention is to provide a cheap, simple, strong, durable and attractive looking clothes rack which may be used on and readily attached or detached from the foot of an iron, brass, or other metallic bedstead.

In the accompanying drawings, Figure 1 is a perspective view of a clothes rack constructed in accordance with my invention, showing the same attached to the foot of an iron bedstead. Fig. 2 is a detail perspective view of my improved clothes rack, on a larger scale.

My improved clothes rack comprises a bar 1 and depending arms 2 at the ends thereof. In practice, and as here shown, the said bar and arms are formed integrally and may be formed from a piece of pipe of suitable length and diameter bent as shown. The said arms 2 are bent at points a suitable distance from the lower ends thereof to form offsets 3, and the said arms are preferably connected together by a cross bar 4 which is disposed at a suitable distance from and below the bar 1, and is here shown as provided with collars or head 5 at its ends through which the arms 2 extend, the said heads or collars being disposed at a suitable height above the offsets 3.

On the front sides of the arms 2 at a suitable distance from the lower ends thereof, are downwardly extending hooks 6, to engage the horizontal rail *a* of the foot or head of a metallic bedstead. In the lower ends of the said arms 2 are clips 7 to bear against the posts *b* of the bedstead. In the embodiment of the invention here shown, the said clips are secured to heads 8 which are secured to the lower ends of the said arms. I do not limit myself in this particular. The cross

bar 1 of the rack, which is disposed, as will be observed by reference to Fig. 1 of the drawing, on the foot or head of the bedstead as the case may be, is provided with outwardly extending hooks 9 for hanging clothes therefrom of which hooks any suitable number may be used, and the said hooks may be of any suitable construction. I also provide the said cross bar 1, preferably at points near the ends thereof, with upstanding pins or studs 10 on which articles, parts or the like, may be placed. It will be understood that my improved rack may be made of any desired size or shape, that it will conform in width to that of the bedstead on which it is to be used, and that it may be readily attached to the bedstead by merely applying the clips 7 to the bedstead and engaging the hooks 6 with the bar *a* of the bedstead.

Having thus described the invention, what I claim as new, is:

1. A detachable clothes rack for bedsteads comprising an upper horizontal bar, arms depending therefrom and provided at their lower ends with clips to bear upon posts of the bedstead, a lower horizontal bar carried by the arms, the latter being formed with offsets below said lower horizontal bar to project the lower ends of the arms in a plane of the upper ends of the arms and the bars, and hooks upon said lower ends of the arms between the clips and offsets to engage a cross bar of the bedstead.

2. A detachable clothes rack for bedsteads comprising an upper horizontal bar, upright arms depending therefrom and having inwardly projecting offsets adjacent their lower ends, the latter being provided with clips to bear upon posts of the bedstead, a lower horizontal arm connected with the arms above said offsets, hooks upon the lower ends of the arms between the clips and offsets to engage a cross bar of the bedstead, and clothes supporting devices on the upper cross bar.

In testimony whereof I affix my signature in presence of two witnesses:

JAMES B. BAUM.

Witnesses:

CHARLES B. RICH,
ED HERVY.
